GUN PERFORATOR

Raymond D. Elliott, Long Beach, Calif., assignor,
by mesne assignments, to Byron Jackson Co.,
Vernon, Calif., a corporation of Delaware

Application October 13, 1944, Serial No. 558,581

14 Claims. (Cl. 164—0.5)

1

This invention relates to bullet shooting devices and has particular application to gun perforators for well casings although it may also be useful in other types of guns.

A general object of the invention is to provide a simpler gun structure by changing the usual detonating elements for exploding the powder charge.

A more specific object is to provide a method of exploding a powder charge in a gun from the muzzle end, thereby eliminating the necessity of providing the usual openings in the rear end of the gun for ignition purposes.

A further object of the invention is to provide a method of discharging a projectile from a gun perforator wherein a concussion responsive propulsive charge is detonated by the concussion from a detonating charge which is detonated in front of the projectile, and which concussion is transmitted by the projectile to the propulsive charge.

A still further object of the invention is to provide a method of discharging a projectile from a gun perforator, characterized by detonating a concussion initiating charge in front of the projectile to force the projectile rearwardly in its gun bore, and, while the projectile is moving rearwardly, detonating a propulsive charge rearwardly of the projectile to discharge it from the gun bore.

A still further object of the invention is to provide a gun perforator in which a bullet is interposed between two explosive charges in the gun bore, and in which the explosive charge in front of the bullet is detonated to force the bullet rearwardly in the gun bore and transmit the force of the detonation to the other explosive charge and thereby detonate the latter charge to discharge the bullet from the gun bore.

Yet another object of the invention is to provide a gun perforator as aforementioned, whereby a number of projectiles may be discharged as aforesaid, the discharge of said projectiles being accomplished by common firing means.

Briefly, to detonate the powder charge in a gun in accordance with the invention, I force the bullet back against the powder with sufficient violence to explode it. The forcing back of the bullet is preferably accomplished by firing a relatively small amount of relatively powerful, fast-acting explosive in front of the bullet. In a gun perforator or similar device having a plurality of firing chambers in a single body, the igniting explosive may be in the form of a continuous fuse extending across the muzzles of all the chambers.

A full understanding of the invention may be had from the following detailed description read in connection with the drawings in which:

Fig. 1 is a vertical section through the upper

2

part of a casing perforating gun incorporating the invention.

Fig. 2 is a cross section taken in the plane II—II of Fig. 1;

Fig. 3 is a cross section taken in the plane III—III of Fig. 1;

Fig. 4 is a cross section showing an alternative shape of gun body to that shown in Fig. 3;

Fig. 5 is a fragmentary section showing a modification of the gun structure shown in Fig. 1; this view being also a section through one of the gun bores of Fig. 6;

Fig. 6 is a detail side elevation showing a modification of the arrangement of Fig. 1; and

Figs. 7, 8 and 9 are views similar to Fig. 5 showing alternative arrangements.

Referring first to Figs. 1 and 2, the gun therein disclosed comprises a solid body 10 adapted to be secured at its upper end in any desired manner to a cable by which it may be lowered into a well casing to be perforated. The cable may contain an insulated electrical conductor 12 which is brought out of the lower end of the cable within an adapter 11 and connected by means of a banana plug 12a on the adapter and a jack 12b in the body 10 to another conductor 14 leading to an electrical fuse 15 which may be of standard type and functions to ignite one end of a fuse-like explosive element 16 which extends longitudinally of the body 10 in a groove 17 provided for it.

As shown, the electrical fuse 15 is sealed by cement 15c within a fuse tube 15a which is held in a pocket provided therefor in the body 10 by a screw 15b so that the fuse is protected against wetting and physical damage during handling of the gun and lowering it into a well.

The groove 17 extends across the muzzles of a plurality of gun bores 19 which, in the particular form of gun shown in Fig. 1, are all positioned in the same vertical plane and are vertically spaced uniformly from each other. Each gun bore 19 is completely closed at its rear end, having no opening whatsoever other than that at the muzzle end which is located in each case at the groove 17.

There is shown in each gun bore 19 a powder charge 20 and a bullet 21, the powder charge being preferably separated from the bullet by a mass of sealing material 22 which prevents entry of water or other fluid past the bullet 21. The sealing material 22 may be a plastic, water-proof preparation such as rubber or plastic sealing compound which is compressed between the powder charge and the bullet when the latter is placed in position.

The bullet is preferably fitted to the gun bore with such tightness that it retains itself in place by friction, although in some instances it may be desirable to employ loosely fitting bullets and

maintain them in place with wadding or plastic placed in front of the bullet as disclosed in my copending application Serial No. 527,110, filed March 18, 1944, now Patent No. 2,402,153, granted June 18, 1946.

As shown in Fig. 1, the fuse-like explosive element 16 is looped into the muzzle end of each gun bore as indicated at 23. In some instances the resistance of the element 16 to bending may offer sufficient frictional engagement to retain the loops 23. However, to insure that they remain in place, each loop may be held in its associated gun bore by a flat wedge 25 of wood or plastic, which wedge is driven into the gun bore until its outer end is flush with the outer surface of the gun. The explosive element 16, although being similar to a fuse in that it consists of an outer flexible, fluid-proof casing containing combustible material, differs from a conventional fuse in that the combustible material employed consists of an explosive having very fast burning characteristics so that when set off by the electrical fuse 15, the whole element 16 explodes practically instantaneously with terrific force. This force acting against the bullets 21 drives them back against their powder charges 20 with sufficient impact to explode the charges. Furthermore, although the powder charges 20 may be of conventional types employed in gun perforators, they seem to explode with more force when set off in the way described than when they are ignited with the usual firing elements. Hence, it appears that when exploded in accordance with the present invention, ordinary powders detonate rather than explode in the usual manner.

It may not be necessary in all instances to loop the element 23 into the muzzle of each gun bore as shown in Fig. 1. In some instances the force of the explosion of the element 16 is sufficient to detonate the powder 20 if the element is simply extended straight across the muzzle. The exact amount or length of the element that must be positioned in or adjacent to the muzzle is dependent upon the explosive properties of the element, the length of the gun bore, the tightness with which the bullet is fitted in the gun bore, the quantity and nature of the sealing member 22 and the character of the powder charge 20, all of which factors may be varied to suit particular circumstances.

Various commercial explosive elements can be employed as the element 16, typical examples of which are sold under the trade names of "Prima-cord," "Mericalcord" and "Cordeau." An explosive that may be used as the core of the element 16 is penta erithritol tetranitrate, the speed of propagation of the wave front of which is, I believe, about 21,000 feet per second.

A great advantage of the construction described is the simplicity of the gun structure itself. It may be forged from a single billet of tool steel and the groove 17 and the gun bores 19 formed by simple conventional machining operations. It is to be particularly observed that no wires, threads and seals are required other than the seal necessary to protect the powder charge from fluids that may be present.

When the gun barrels or bores are all positioned in a single vertical plane, the cross section of the gun body need not necessarily be circular as shown in Fig. 3. Instead it might be rectangular as shown at 10a in Fig. 4, in which case some material can be saved and a turning operation eliminated. The elimination of as much machine work as possible is desirable be-

cause the gun body must usually be made of high quality tool steel which is expensive, in addition to being relatively difficult to machine. High quality steel is desirable, if not essential, in order to secure the necessary strength to withstand the violent explosive forces that are employed and to reduce the wear of the gun bores from repeated use. Special steel known in the trade as "Omega" steel has been found satisfactory, although various other steels may be equally suitable.

It may be desirable in some instances to distribute the different gun bores 19 in the cylindrical body of Fig. 1 so that different bullets are shot in different directions. There is shown in Fig. 6 a construction in which the different gun bores are arranged with their muzzles in a helical path extending around a cylindrical body 10b, in which case the groove 17b containing the detonating element is in the form of a helix extending across the gun muzzles.

There is also shown in the detail view of Fig. 5 a different manner of providing additional quantities of the detonating element in the muzzle of each gun bore. Thus in the construction of Fig. 5, the main element 16c is extended straight across the gun muzzles but a short piece 27 of the explosive element is looped around the element 16c at each gun bore and the ends extended into the gun bore. The friction of the elements 27 against the walls of the gun bores is relied upon to retain them in position.

In the arrangement of Fig. 7 additional explosive force is obtained by placing a capsule 38 of fluid-resistant, yieldable material within the gun bore in front of the bullet 21d, the capsule containing a suitable explosive.

In any of the arrangements shown in the drawing, the force applied to the bullet may be increased by applying a gob of quick drying cement over each muzzle as the final operation. The cement acts as stemming to increase the force of the explosion in the opposite direction, that is, into the muzzle.

An alternative arrangement of the gun barrels to those disclosed in Figs. 1 and 2 is to arrange them all in a single vertical plane but have successive barrels pointing in opposite directions so that the recoil forces are more or less balanced. Such a gun may be of circular cross section as shown in Fig. 3 or of rectangular cross section as shown in Fig. 4. Detonation may be effected by employing two separate elements 16 in two grooves corresponding to the grooves 17 positioned on opposite sides of the body or a single explosive element positioned in a helical groove extending across all the gun muzzles may be employed as shown in Fig. 6.

Although the adapter 11 may be secured to the body 10 in various manners, a particularly effective way is to employ a snap ring 31 which normally expands to completely fill a shallow groove 32 in the body and extend in the groove 33 in said adaptor 11. The ends of the ring are bent out into a recess 34 in the body and by squeezing the ends of the ring together, the ring can be collapsed completely within the groove 33 to permit release of the adapter from the body 10. A rubber washer 47 is provided between the lower end of the adapter and the body to reduce leakage of current from the banana contact 12a and jack 12b to the body 10 in the presence of conductive fluids.

The use of the removable fuse tube 15a permits rapid reloading of the gun in the field, since a number of extra tubes having fuses cemented

therein may be kept on hand. Each fuse 15 may be connected to its tube by a soldered lead 35 to complete the circuit to ground.

The explosive cord 16 may, in some instances, advantageously consist of metallic tubing such as lead or copper, filled with an explosive having the necessary characteristics. The metal will resist the action of the fluids present in some wells better than the impregnated fabric coverings commonly used on such fuse structures.

If desired, separate gun barrels may be employed as shown in Fig. 8 in which barrels 36 are freely fitted in sockets 37 provided therefor in the body 10c and detachably retained in place with snap rings 38 functioning the same as the snap ring 31 of the adapter 11. The use of the separate gun barrels facilitates reloading of the gun in the field since a supply of loaded barrels may be carried along. This manner of securing barrels in their sockets is disclosed in my copending application Serial No. 527,110, now Patent No. 2,402,153, granted June 18, 1946.

There is disclosed in Fig. 9 an alternative method of driving the bullet back to explode the main charge. In this embodiment, a charge of explosive 40 is placed in the bore 19f in front of the bullet and sealed against fluid by a disk 41 pressed into a shallow counterbore at muzzle end of bore 19f. To explode the charges 40 a longitudinal hole 42 intersecting the bores 19f may be provided and the hole filled with powder which is ignited by an electrical fuse 15f at the upper end. To limit dissipation into the hole 42 of pressure developed in the gun bores 19f, screw plugs 44 having small transverse passages 45 therein may be screwed into tapped holes provided therefor immediately above and below each gun bore 19f, which plugs can be replaced when their passages 45 have been eroded by use.

When the system of Fig. 9 is used, the explosive may be any one of many known types. One that is suitable is a double base pistol powder such as the product of the Hercules Powder Co. known in the trade as "Bull's Eye" brand.

It will be observed from the foregoing description of several forms which the invention may assume, that in each instance the propulsive charge 20 is detonated by the concussion or detonation force of detonation means disposed in front of the bullet, the detonation force of which is transmitted to the propulsive charge by the bullet. This novel firing method and arrangement possesses several distinct advantages over other known firing methods and arrangements. The gun structure is thereby rendered simpler and less costly to manufacture, since the gun bores are open only at one end and no auxiliary passages are required to afford access to the powder chamber rearwardly of the bullet. Furthermore, the elimination of such other passages simplifies the problem of sealing the powder chamber from the fluid in which the gun is usually immersed when fired.

Another important aspect of this invention relates to the greatly increased propellant effect of the powder charge when detonated by this method. I have discovered that certain explosives of the propulsive type, such as that sold under the trade name "Bull's Eye," are in fact what may be termed self-detonating concussion responsive explosives which can be detonated by concussion alone, without the aid of primers or detonation initiators. Furthermore, I have found that when such an explosive is detonated in this manner its propellant effect is greatly enhanced.

This increased propellant effect is of utmost importance in gun perforating of well casing, for obvious reasons. The gun bores of gun perforators are necessarily relatively short, and, in order to impart the necessary muzzle velocity to the bullets, various expedients have heretofore been resorted to, such as the provision of frangible disks or the like to retard movement of the bullets until the pressure developed by

10 the explosion of the propulsive charges reaches a predetermined magnitude. I have found, however, that by firing in accordance with my method a very high muzzle velocity is attained without the use of such retarding devices. It is self-evident that when a retarding device such as a frangible disk is employed, a substantial portion of the energy developed by the explosive is consumed in shearing the disk, and for this reason such devices at least partially defeat their 15 own purpose. The attainment of sufficient muzzle velocity by the manner of detonating the propulsive charge, in contradistinction to the use of retarding devices, is therefore considered to be a great forward step in this art.

20 Another factor contributing to the increased muzzle velocity is the fact that the pressure wave from the detonation of the explosive charge in front of the bullet is effective to momentarily retard the outward movement of the bullet and thus allow the pressure behind the bullet to rise to a relatively high value before the bullet starts to move. The peak of the pressure wave in front of the bullet is reached substantially simultaneously with the initiation of the explosion in back

25 of the bullet, and, as the pressure behind the bullet increases, the pressure in front of the bullet decreases. The bullet obviously cannot move forwardly until the pressure behind the bullet exceeds that in front of the bullet, and when this 30 condition prevails the pressure behind the bullet has reached a high value. The pressure in front of the bullet decreases very rapidly due to the rapid cooling of the gases by the surrounding liquid, and consequently by the time the bullet

35 has moved a very short distance the pressure wave in front thereof has subsided to substantially the hydrostatic pressure of the liquid.

40 Still another factor which contributes to increased muzzle velocity and greater penetrating 45 effect of the bullets is the fact that as the bullet moves forwardly the path of the bullet is filled with gas from the detonation of the charge in front of the bullet. Ordinarily, when a gun perforator is fired by other known methods, the bullet 50 lets are projected through a body of liquid, which obviously offers more resistance than a body of gas. Consequently, by this method of firing there is materially less decrease in velocity of the bullet between its emergence from the gun bore and 55 its contact with the casing.

60 Although an important phase of this invention relates to the detonation of the propulsive charge by the rearward concussion transmitted thereto by the bullet from the detonation of an explosive 65 charge in front of the bullet, it will be appreciated that the advantages resulting from this method of firing are attained even though detonation of the propulsive charge by concussion may be assisted or augmented by the use of priming means. Hence it is to be understood that priming means may be used, if desired, and the terms "propulsive charge" and "explosive means," 70 as used in the appended claims, do not necessarily exclude priming means associated with the powder charge.

Although for the purpose of explaining the invention certain specific embodiments thereof have been described in considerable detail, many changes from the exact construction shown may be made without departing from the invention which is limited only to the extent set forth in the appended claims.

I claim:

1. A gun perforator, comprising: a gun body structure defining a plurality of laterally directed gun bores; bullets in said gun bores; concussion responsive explosive means in said gun bores rearwardly of said bullets; and fuse-like detonation means passing along said gun body and traversing the muzzle ends of said gun bores.

2. A gun perforator as set forth in claim 1, in which said gun body structure is provided with an external groove intersecting the muzzle ends of said gun bores and adapted to receive said fuse-like detonation means.

3. A gun perforator comprising: a gun body structure defining a plurality of laterally directed gun bores angularly disposed with respect to each other; bullets in said gun bores; concussion responsive explosive means in said gun bores rearwardly of said bullets; and fuse-like detonation means wrapped helically about said gun body structure and traversing the muzzle end of each of said gun bores.

4. A gun perforator as set forth in claim 3, in which said gun body structure is provided with a helical groove intersecting the muzzle ends of said gun bores and adapted to receive said fuse-like detonation means.

5. A gun perforator comprising: a gun body structure defining a plurality of laterally directed gun bores; bullets in said gun bores; concussion responsive explosive means in said bores rearwardly of said bullets; detonation means in said bores in front of said bullets; and common means for detonating all of said detonation means.

6. A gun perforator comprising: a gun body structure defining a plurality of laterally directed gun bores; bullets in said bores; concussion responsive explosive means in said bores rearwardly of said bullets; first detonation means in said bores in front of said bullets; and fuse-like detonation means passing along said gun body structure in detonating relation to each of said first detonation means.

7. A gun perforator comprising: a gun body structure defining a plurality of gun bores; bullets in said gun bores; concussion responsive explosive means in said gun bores rearwardly of said bullets; walls defining a passage within said gun body structure and communicating with each of said gun bores; detonation initiating means in said passage; and detonation means in each of said gun bores in front of the bullets in position to be detonated by said detonation initiating means.

8. The method of discharging projectiles from the gun bores of a gun perforator, which comprises: exploding primary detonation means in close proximity to the muzzle ends of said gun bores; exploding secondary detonation means in said gun bores in front of the projectiles by the force of said primary detonation means; transmitting by the projectiles the force of said detonation means to concussion responsive explosive means in said gun bores rearwardly of said projectiles; and detonating said concussion responsive explosive means by said transmitted force to discharge the projectiles from the gun bores.

9. A well casing perforating gun comprising: a body having a plurality of firing barrels therein, each barrel being adapted to be loaded with a projectile, a propelling charge between the projectile and the closed rear end of the barrel, and a priming charge between the projectile and the discharge end of the barrel, and common igniting means associated with the respective discharge ends of the barrels and adapted to cooperate with the several priming charges in exploding the latter so as to drive the respective projectiles rearwardly, compressing the propelling charges to a point where the latter are exploded so as to drive the projectiles from the barrels.

10. A perforating gun as defined in the preceding claim wherein the discharge ends of the barrels are arranged in helical formation around the body and the body is provided with a helical groove associated with said discharge ends and adapted to receive said common igniting means.

11. A gun having barrels adapted for the use of loads each consisting of a projectile, a propelling charge adjacent the rear end of the projectile, a priming charge adjacent the front end of the projectile adapted to be fired by a priming cord, and a closure to seal the front end of the barrel, comprising: a gun body having a plurality of gun barrels extending thereinto from the exterior to receive said loads, and a passage in said body to receive said priming cord, communicating with the portions of said barrels which receive said priming charges; and means for igniting said priming cord.

12. In a gun wherein a propelling charge adjacent the rear end of a projectile is ignited by driving the projectile rearwardly in the gun barrel: a gun body having a plurality of barrels leading in from the exterior thereof and a priming cord passage extending within the body, said priming cord passage communicating with the portions of said barrels between the outer ends of the projectiles and the outer ends of the barrels.

13. In a gun wherein a propelling charge adjacent the rear end of a projectile is ignited by driving the projectile rearwardly in the gun barrel: a gun body having a plurality of barrels leading in from the exterior thereof and a priming cord passage extending within the body, said priming cord passage communicating with the portions of said barrels between the outer ends of the projectiles and the outer ends of the barrels; and means to close the outer ends of said barrels.

14. A gun perforator, comprising: a gun body structure defining a gun bore; a bullet slidably rearwardly in said gun bore; concussion responsive explosive means in said gun bore in back of said bullet, and a primer cell in said gun bore in front of said bullet, said primer cell including a wall engageable with the nose of said bullet and a second wall cooperating with said front wall to form a chamber for an explosive.
